CLAIM

The ornamental design for a dishwasher door with a control panel, as shown and described.

DESCRIPTION

FIG. 1 is a front perspective view of a dishwasher door with a control panel showing our new design;

FIG. 2 is a front view of the dishwasher door with the control panel of FIG. 1;

FIG. 3 is an enlarged front view of the dishwasher door with the control panel of FIG. 2;

FIG. 4 is a top view of the dishwasher door with the control panel of FIG. 1; and,

FIG. 5 is a right side view of the dishwasher door with the control panel of FIG. 1, the left view being a mirror image. The broken lines in the figures illustrate the portions of the design that form no part of the claimed design.

1 Claim, 5 Drawing Sheets
